UNITED STATES PATENT OFFICE.

AIKEN C. TAYLOR, OF RICHMOND, VIRGINIA, ASSIGNOR TO EMANUEL P. SUMMERFIELD,
OF NORFOLK, VIRGINIA.

WEATHER-STRIP.

1,223,445.

Specification of Letters Patent.

Patented Apr. 24, 1917.

Application filed June 27, 1916. Serial No. 106,184.

To all whom it may concern:

Be it known that I, AIKEN C. TAYLOR, a citizen of the United States, residing at Richmond, in the county of Henrico, State 5 of Virginia, have invented certain new and useful Improvements in Weather-Strips; and I do hereby declare the following to be a full, clear, and exact description of the invention, such as will enable others skilled in 10 the art to which it appertains to make and use the same.

This invention relates to a weather strip.

An object of the invention resides in the provision of an improved metallic weather 15 strip which will effectively prevent the passage of the weather between the window frame and the sash.

A further object of the invention resides in so constructing the strip that it may be 20 applied to both the frame and the sash without removing the latter from the former.

A still further object of the invention resides in so constructing the device that a 25 weather-tight joint will be maintained irrespective of whether or not the sash should shrink.

A still further object of the invention resides in so constructing the strip that it may be 30 applied without materially altering the present construction of the frame and without altering in any way the construction of the sash such as cutting or grooving the same.

A still further object of the invention resides in so constructing the device that the rattling of the window will be effectively 35 prevented irrespective of whether the sash are raised or lowered.

A still further object of the invention resides in the provision of a strip which will 40 effectively drain the water from the sash and prevent its entry beneath the lower sash.

In the drawing:

Figure 1 is a vertical sectional view 45 through a window frame with the sash in place therein showing my invention applied thereto;

Fig. 2 is a similar view taken at right angles to Fig. 1, only a portion of the frame 50 being shown however;

Fig. 3 is an enlarged detail sectional view taken through the sash and frame and showing the manner in which the strip on the sash coöperates with the metallic bead and how the latter coöperates with the frame; 55

Fig. 4 is a detail perspective view looking at the lower corner of the frame and the lower sash, parts thereof being broken away to clearly disclose the strip on the sash;

Fig. 5 is a detail of the stripping used to 60 seal the joint between the lower rail of the outer sash and the upper rail of the inner sash, and

Fig. 6 is a detail of the stripping used to 65 seal the joint at the lower end of the lower sash.

In the drawing, I have illustrated a portion of a window frame 1 and upper and lower sash 2 and 3 respectively. The frame 1 is of the usual form having stops 4 and 5 70 at its inner and outer edges and having a groove 6 extending longitudinally thereof for the reception of the bead which separates the sash.

In order that the weather may be 75 prevented from passing between the sash and the frame, I have provided a metallic separating bead 7 which is U-shaped in cross section and the sides 8 of which are resilient and diverge from the face 9 in the manner 80 clearly illustrated in Fig. 3 of the drawing. One of these beads is inserted in the groove 6 in each of the side rails of the frame and in the top rail 10 thereof. The beads however extend outwardly beyond the grooves 85 so as to effectively guide the sash and the sides 8 of the bead are located in slight spaced relation to the sides of the grooves 6 leaving spaces 11. These beads are secured in position within the grooves 6 by 90 means of screws 12 surrounding which are sleeves 13 which are of slightly greater length than the widths of the sides 8 so that when the inner ends of these sleeves bear against the bottoms of the grooves 6 the 95 edges 14 of the sides 8 will be in slight spaced relation to the said bottoms and consequently free to move by virtue of their resiliency. It is to be noted that this bead may be applied to the frame of the types 100

used at the present time without necessitating the change of construction of the frame other than the removal of the present wooden beads and without necessitating the removal of the sash. Secured to the inner face of the upper sash and to the outer face of the lower sash are flat metallic strips 15 which project beyond the sides of the sash and into the spaces 11 between the sides 8 and 10 of the beads and the sides of the grooves 6. The inner edges of these strips 15 are slightly upset so that when the strips are attached to the sash the upset edges will bite into the rails of the sash and form a tight joint.

The resilient sides 8 of the beads 7 will force the strips 15 tightly into contact with the sides of the grooves 6 so that an absolutely weather-tight joint is formed. It is to be noted in this connection that even if the sash shrink so that the strips 15 are withdrawn from the spaces 11 to a slight extent the resilient sides of the beads 7 will continue to force the strips 15 into contact with the sides of the grooves 6 so that the weather-tight joint will be maintained.

In the drawing I have illustrated the weather strip as applied to the sides and top of the frame and have illustrated a convenient form of strip for sealing the joint between the lower rail of the outer sash and the upper rail of the inner sash. I have further illustrated a strip for sealing the joint between the frame and the lower rail of the inner sash which includes a portion 16 which is secured to the frame and extends upwardly at right angles thereto and a portion 17 which is secured to the lower rail of the inner sash and is bent outwardly so as to receive the upwardly extending portion 16. This will form an effective joint and will not only prevent the entrance of the weather but, because of the peculiar formation of the portion 17, will shed the water.

It will thus be seen that I have provided a weather strip which includes essentially beads carried by the frame and strips carried by the sash both of which may be put in place without necessitating the removal of the sash from the frame or any change in the frame or sash whatsoever with the exception of the removal of the dividing bead from the frame and the substitution of my improved bead therefor. Furthermore I have provided a device which will at all times, irrespective of the position of the sash, due to shrinkage, form a perfectly weather-tight joint. Furthermore I have provided an article of manufacture which may be cheaply and easily manufactured and which may be installed by a layman with only the ordinary skill.

While I have illustrated and described a particular embodiment of my invention, it has merely been for the sake of convenience

and I do not wish to be limited to that particular embodiment as it is obvious that numerous changes may be made in the details of construction without departing from the spirit of the invention or exceeding the scope of the appended claims.

What I claim is:—

1. The combination with a window frame having a bead groove therein and a sash, of a bead having a resilient freely movable side located in the bead groove of the frame and a strip secured to the sash and engaging the resilient side of the bead and being pressed into engagement with the adjacent side of the groove by said bead. 75

2. The combination with a window frame having a fixed face extending inwardly of the frame, of a bead having a resilient freely movable face opposed to said rigid face of the frame, a sash slideable in the frame and a strip carried by the sash and engaged frictionally between said rigid face of the frame and the resilient face of the bead. 85

3. The combination with a window frame having a bead groove therein, of a parting bead mounted in said groove and having resilient diverging sides located within the groove in spaced relation to the sides thereof, a sash at each side of the parting bead, each sash having a strip thereon projecting into the groove in the frame between the corresponding sides of the bead and groove and engaging the said sides of the bead and the side of the groove. 90

4. The combination with a window frame having a bead groove therein, of a bead mounted in said groove and having resilient sides, the bead being of lesser width than the groove, a sash at each side of the bead having a strip thereon which extends into the groove between the bead and the corresponding side of the groove, the thickness of the strip being greater than each space between the corresponding side of the bead and the side of the groove. 100

5. A parting bead for window frames including a body portion U-shaped in cross section and having resilient sides, screws extending through the bead between the sides thereof and sleeves encircling the screws, 115 which sleeves are of greater lengths than the widths of the sides.

6. The combination with a window frame having a bead groove therein, of a bead, U-shaped in cross section, mounted on the frame and having its sides extending into the groove in spaced relation to the sides thereof and terminating in spaced relation to the bottom of the groove, screws passing through said bead and engaging the frame 120 and sleeves encircling the screws and maintaining the sides of the bead in spaced relation to the bottom of the groove. 125

7. The combination with a window frame, of a bead including a resilient plate carried 130

by and extending inwardly of the frame, said frame having a fixed face extending inwardly thereof and at an angle to the plate, a sash slidably mounted in the frame and 5 a strip carried by the sash and extending between and in contact with the resilient bead plate and said fixed face of the frame.

In testimony whereof, I affix my signature, in the presence of two witnesses.

AIKEN C. TAYLOR.
